UNITED STATES PATENT OFFICE.

LAWRENCE BRADY, OF PHILADELPHIA, PENNSYLVANIA, ASSIGNOR TO
MICHAEL HAYDEN, OF SAME PLACE.

POWER-HAMMER.

SPECIFICATION forming part of Letters Patent No. 241,285, dated May 10, 1881.

Application filed December 14, 1880. (No model.)

To all whom it may concern:

Be it known that I, LAWRENCE BRADY, a citizen of the United States, residing at Philadelphia, in the county of Philadelphia and State 5 of Pennsylvania, have invented new and useful Improvements in Power-Hammers, of which the following is a specification, reference being had to the accompanying drawings, wherein—

10 Figure 1 is a side elevation of a power-hammer embodying my improvements, and Fig. 2 is a side elevation of the improvements.

My invention has reference to the improved machine for heading bolts, for which Letters 15 Patent of the United States, dated July 8, 1879, No. 217,327 were granted to me and Michael Haydon.

My present improvements have for their principal object to provide means for holding 20 up the hammer while the headed bolt is being removed from and the blank is being inserted in the die.

My improvements have for their further object to provide means for easing or cushioning 25 the operating-crank on its upstroke.

My improvements consist, first, in the provision of a support for holding up the hammer while the headed bolt is being removed from and the blank is being inserted in the die, said 30 device being controlled by the treadle which moves the clutch on the crank-shaft to start and stop the latter; second, in the provision of a top yielding plate in the crank-lever, said plate being located opposite to the lower yielding plate, (shown in the patent above mentioned,) and being designed, as already stated, 35 to ease the crank on its upstroke.

Referring to the accompanying drawings, A represents the crank, (shown in the patent 40 above named,) and B the lever which it vibrates.

C is the lower yielding plate. (Shown in said patent.) C' is another yielding plate of like construction, located on said lever B, opposite 45 the plate C, and operating to ease or cushion the crank on its upstroke.

D is the treadle, by means of which the clutch d is thrown on and off to start the crank-shaft so as to operate the lever B.

50 E shows another lever, whose lower end, e,

is fitted between studs d' d' on the treadle D, so as to be vibrated on its fulcrum e' whenever said treadle is moved.

F shows a slide sustained on an arm, G, pivoted between uprights g g, which are sustained 55 on projections H H, mounted on the frame of the machine. The arm G is connected by a chain, K, to a spring-bar, k, so as to permit it to yield elastically whenever the hammer drops on the slide F. Said chain is provided with a 60 turn-buckle, k', whereby the amount of motion of the arm G may be regulated or adjusted. Said slide has a projecting stud, f, which works in an elongated slot, e², in the lever E, so that whenever the treadle is depressed by the operator's foot the slide will be drawn backward, while, whenever the treadle is relieved of pressure, the said slide will be projected forwardly under the influence of the spring d², and caused to come in the path or in the line of descent 65 of the hammer-handle n. In this location it affords a rest for the hammer N, and holds the latter in an elevated position over the die, so as to permit the operator free access to the latter for the purpose of removing the headed 70 bolt from and inserting the blank therein. As soon as the blank is duly inserted in the die the operator depresses the treadle with his foot, thereby drawing back the slide out of the path of the hammer-handle. At the same time 75 and by the same motion he brings the crank-shaft into clutch engagement, causing said crank to vibrate the lever B and the hammer to strike. As soon as the bolt has been headed the operator relaxes his foot-pressure on the 80 treadle, whereupon the clutch, being thrown out by the spring d², ceases to engage with the crank-shaft, and the slide F moves forward 85 into the path of the hammer-handle and receives the latter, supporting it in an elevated 90 position until the headed bolt has been withdrawn from the die, a fresh blank inserted, and the crank-shaft again set in motion.

What I claim as my invention is as follows:

1. In a bolt-heading machine or "oliver," the 95 combination, with the hammer, the crank-shaft, and clutch mechanism, of a movable support for sustaining said hammer in an elevated position, said support being connected with the operating-treadle, which is also connected with 100

the clutch mechanism, whereby, when the mechanism for operating the hammer is brought into operation, said support is moved out of the path of the hammer, substantially as set forth.

2. The combination, with the treadle D and hammer N n, of the lever E, arm G, and sliding hammer-support F, substantially as set forth.

3. In combination with the crank A and lever B, the top yielding plate, C', for cushion-

ing the said crank on its upstroke, substantially as shown and described.

In testimony that I claim the foregoing I have hereunto set my hand this 9th day of October, 1880.

LAWRENCE BRADY.
